PNEUMATIC ICE TRAY AND CUBE RELEASE

Logan L. Mallard, Norfolk, Va.

Application December 4, 1941, Serial No. 421,646

11 Claims. (Cl. 62—108.5)

1

This invention relates to refrigeration and more particularly to the freezing unit and trays associated therewith in which water or other matter is placed for freezing or congelation.

Removing an ice tray from the support upon which it is frozen and removal of cubes from the tray has been a recognized problem and numerous attempts have been made toward a solution of this problem. The present invention is directed likewise to a solution of this problem above stated, it being an object of the invention to provide (1) an improved means for breaking the ice bond between a tray and its support so that the tray may be easily removed from the cooling unit, and (2) also improved means for freeing the cubes from the tray after the tray is removed so that the cubes may be readily accessible for use.

The present invention utilizes fluid pressure means for freeing the tray from the support to which it is frozen and for freeing the cubes from the walls of the cells of the tray in which they are formed. An expansible diaphragm or other member movable under the influence of fluid pressure is located between a portion of the tray and its supporting shelf, and this member is operated by fluid pressure supplied thereto by some suitable means, such as for example as by a manually operated pump. The ice tray is provided with a pressure area or chamber and the bottom of each ice cube cell is movable or flexible to facilitate removal of the ice cubes. The tray is also provided with a valve inlet so that compressed air or other fluid may be introduced into said area or chamber to flex the bottoms of the cells and free ice cubes therefrom. The construction is such that the compressed air or other fluid pressure for freeing the cubes may be supplied from the same source as that for freeing the tray from its support.

The foregoing and other objects and advantages of the invention will become apparent in view of the following description taken in conjunction with the drawing, wherein:

Fig. 1 is a front elevation of a refrigerator embodying the invention, the refrigerator door being broken away to reveal the evaporator and coacting tray dislodging means;

Fig. 2, an enlarged section taken substantially on the line 2—2, Fig. 1;

Fig. 3, an enlarged view of a portion of Fig. 2 showing the tray dislodging means in operation;

Fig. 4, an enlarged fragmentary sectional elevation of the evaporator and adjacent wall por-

2

tion of the refrigerator with a tray in position to have its cubes released;

Fig. 4a is a fragment of the tray of Fig. 4 showing the flexible bottom or diaphragm of one of the grid compartments in normal freezing position;

Figs. 5 and 6, respectively, enlarged detail sectional views of a pneumatic bellows or foot pump and air-release nozzle.

10 As shown on the drawing a refrigerator cabinet 10 of conventional construction is provided with a door 11 affording access to the food compartment 12. Within the food compartment is located a refrigerating unit 13 having shelves 14 between 15 which are a series of compartments 15 adapted to receive trays 16 for containing matter to be frozen or congealed.

A tray releasing member 17 is associated with one or more of the shelves 14 in a position to engage the tray for breaking the ice bond between the tray and the shelf thereby freeing the tray from the shelf after its contents have been frozen. This tray releasing member is preferably expansible or inflatable and as shown is a metallic envelope or diaphragm of thin metal which may be of good heat conducting properties to provide maximum heat transfer, although the same is not necessary. Means is provided for accommodating this tray freeing member, and accordingly for the purpose of illustration although not in a restrictive sense, the tray is provided with a recess or depression 18 to receive the releasing element 17 as shown particularly in Figs. 2 and 3.

The tray release 17 is preferably of a size commensurate with the tray to be used and is adapted to be inflated by air or other fluid from any desired source, as for example, a foot pump 20 mounted in the vicinity of the base of the cabinet to be readily accessible for foot operation. The pump 20 consists of a cylinder having a piston 21 reciprocable therein maintained in its upper position by means of a spring 22. A foot lever 23 is provided with a pedal 23', said lever being pivoted at its one end to a bracket 24 and at 45 an intermediate point being slidably or movably connected to the stem of piston 21, note Fig. 5. A tube 25 connects at its one end to the pump chamber and leads upwardly and is provided with a series of branch connections 26 which are connected to their respective expansible tray-releasing members 17.

Figs. 1 and 2 show the ice cube trays in normal freezing position with the expansible tray-releasing members 17 lying flat in their respective recesses 19 on the shelves 14 of the evaporator,

while Fig. 3 shows one of the members 17 expanded to break the ice bond between a tray and the shelf on which it rests. In this manner, one or more trays may be dislodged by simply manipulating the foot, leaving the hands free to remove the trays or for other purposes.

To dislodge ice cubes from the grid sections of the respective freezing trays, the bottom of each grid compartment is provided with a flexible diaphragm 27 and beneath the series of grid compartments is a hollow air-pressure chamber 28, note Fig. 4. At its one end the tray is provided with a socket 29 having projecting from the center thereof a push rod or stem 29'. A branch tube 30 connects into the air-pressure system at the upper end of tube 25 and projects outwardly through the adjacent wall of the cabinet. A valve cage or nozzle 31 is connected to the outer end of the branch tube 30 and has therein a valve in the form of a ball 32 which is spring-pressed against its seat at the front or outer end of the cage, the latter being provided with an exterior flexible sealing gasket 33 to prevent leakage of air when engaging the socket 29.

When it is desired to dislodge ice cubes from the grid compartments of any of the trays 18, it is only necessary to press the socket 29 of the tray against the valve cage 32, thereby causing stem 29' to unseat the ball valve 32 and permitting air to be injected into the air chamber 28 and act on the expansible diaphragms 27 by simply manipulating the foot pedal 23. When pressure is relieved from chamber 28, the diaphragm 27 flexes downwardly against the bottom wall of the tray, as illustrated in Fig. 4a, making contact for good thermal conductivity.

From the foregoing, it will be seen that any one or more of the evaporator trays may be readily dislodged from the evaporator shell and for ice cubes dislodged from the grid compartments of the tray by a simple manipulation of the foot, leaving the hands free to handle the trays.

It will be understood that certain limited changes in construction and design may be adopted without departing from the spirit and scope of the invention as defined in the appended claims.

What is claimed is:

1. In a refrigerator having an evaporator provided with a freezing compartment, a shelf in said compartment, a tray removably disposed on said shelf, a hollow expansible member interposed between said tray and shelf, foot actuated hydraulic means providing a source of fluid under pressure, a conduit communicating said hydraulic means with said expansible member and whereby upon actuation of said hydraulic means fluid under pressure is injected into said expansible member to dislodge the tray from said shelf.

2. In a refrigerator having a food compartment and an evaporator disposed in heat transfer relationship with respect to said food compartment, said evaporator being provided with a freezing compartment, a shelf in said freezing compartment, a tray removably disposed on said shelf, a hollow expansible member positioned between said shelf and tray, a source of fluid under pressure including a foot-actuated hydraulic pump having a pressure chamber, a conduit communicating said pressure chamber with said expansible member and whereby when said pump is operated fluid under pressure is injected into said expansible member to dislodge the tray from said shelf.

3. In a refrigerator having a food compartment,

a cooling unit disposed in heat transfer relationship with respect to said food compartment, said cooling unit being provided with a freezing compartment, a tray removably disposed in said freezing compartment, thin-walled fluid expansible means of good thermal conductivity disposed between the wall of said freezing compartment and said tray, and means for injecting fluid under pressure into said expansible means to dislodge said tray from said wall.

4. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

5. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

15 6. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

20 7. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

25 8. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

30 9. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

10 10. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

15 11. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

16 12. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

17 13. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

18 14. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

19 15. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

20 16. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

21 17. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

22 18. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

23 19. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

24 20. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

25 21. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

26 22. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

27 23. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

28 24. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

29 25. In a refrigerator, a cooling unit having a freezing compartment, a tray removably disposed in said freezing compartment, a wall on which said tray rests, said wall having a depression formed therein, a hollow expansible member disposed in said depression, a source of fluid under pressure, and a conduit communicating said source with said expansible member whereby upon injection of fluid under pressure into said member the ice bond is broken between said tray and wall.

tion of said socket with said nozzle the valve is unseated to permit introduction of fluid under pressure into said chamber.

10. For use in a refrigerator having a cooling unit and a freezing compartment, a tray adapted to be positioned in said freezing compartment and said tray in turn being provided with one or more freezing compartments and a fluid pressure chamber, each of said tray compartments having a flexible wall subject to pressure in said chamber, said tray being also provided with a socket opening into said pressure chamber, a source of fluid under pressure, a conduit communicating with said source and terminating in a nozzle accessible from the exterior of the refrigerator, a normally seated yieldable valve in said nozzle, means in said tray socket cooperative with said valve whereby when the tray is brought into a position effecting cooperation of said socket with said nozzle the valve is unseated to permit introduction of fluid under pressure into said chamber, said source of fluid including a foot actuated pump.

11. For use in a refrigerator having a cooling unit and a freezing compartment, a tray adapted to be positioned in said freezing compartment and said tray being provided with one or more grid compartments and a fluid pressure compartment, the bottom walls of said compartments being flexible, a source of fluid under pressure, conduit means extending from said source and terminating in an exteriorly accessible nozzle having a depressible valve member controlling discharge from said nozzle, said tray being provided with a socket in communication with said fluid pressure compartment and said socket having a valve unseating member disposed therein and arranged so that when the tray is brought into a position effecting cooperation of said socket with said nozzle the valve is unseated to permit introduction of fluid under pressure into said fluid pressure compartment to flex the bottoms of said grid compartments and dislodge matter therefrom.
